DRAWER FOR A SHOE CHEST Arthur G. Cashman, 8320 Oxon Hill Road,
Washington, D.C. 20022

Filed Oct. 25, 1968, Ser. No. 14,181

Term of patent 14 years

Int. Cl. D6—01

U.S. Cl. D33—6

FIG. 1.

FIG. 2.

FIG. 1 is a perspective view of a drawer for a shoe chest showing my new design; and

FIG. 2 is a cross-sectional view, taken substantially in the plane of the line 2—2 in FIG. 1.

The undisclosed side and back of the drawer are conventional.

I claim:

The ornamental design for a drawer for a shoe chest, as shown and described.
